BY-PASS VALVE MECHANISM

Ralph Erling, Cranford, N. J.

Application April 3, 1936, Serial No. 72,658

6 Claims. (Cl. 60—52)

(Granted under the act of March 3, 1883, as
amended April 30, 1928; 370 O. G. 757)

This invention relates to means for equalizing the pressure, at the end of a working stroke, in two cooperating cylinders of a hydraulic power mechanism so related functionally that one of them is subjected to pressure while the other is subjected to suction.

Among the objects of this invention are: To provide valve means that will be automatically actuated at the end of a working stroke to equalize the pressures of the pressure and suction sides of the hydraulic mechanism; to dispose the said valve means in such manner that the proper valve will be opened at the correct time by a member actuated by the hydraulic mechanism; to provide for connecting a valve in such relation that no packing around the valve stem is required; to provide movement amplifying means to assure the sufficient throw of a valve operated thereby.

In the drawings:

Figs. 1 and 2 illustrate my invention applied to a system having two pairs of hydraulic cylinders and rams cooperating therewith;

Figs. 3 and 4 each shows the present invention associated with a single pair of cylinders and cooperating ram;

Fig. 5 discloses the valve opening means mounted on the cross-head pin, the mechanism being shown in longitudinal section;

Figs. 6 and 7 show motion amplifying means to increase the throw of the valve; and

Figs. 8 and 9 are sectional views of two forms of valve housings used in my invention.

For convenience of description, the present invention is shown and described in connection with the steering gear of a ship, but it is to be understood that the subject device is useful in many other applications of hydraulic mechanisms.

It is known to those familiar with the type of hydraulic mechanism here under consideration that it is desirable to provide means for connecting the pressure side of the mechanism to the suction side thereof at the end of each full working stroke to prevent damage to the mechanism by driving any part thereof into a stop under full power. The present invention affords a simple and reliable system for accomplishing this result.

In Fig. 1 the cylinders 10 and 11 are aligned and have a ram 12 operable in both. Cylinders 13 and 14 and ram 15 are disposed adjacent to cylinders 10 and 11 with their longitudinal axes parallel to the longitudinal axes of the first mentioned cylinders, the rams 12 and 15 being connected together by a crosshead 16 secured on rudder post 17. On cylinders 10 and 13 are mounted valve housings 18 and 19 having in them chambers 20, 21, and 22, 23, respectively, with valves 24 and 25 seated in passages between the chambers in the respective housings. The valves 24 and 25 have stems 26 and 27 project-

ing beyond the housings towards crosshead 16 with springs 28 on the stems between the adjustable nuts 29 and the wall of the housing to retain the valves seated.

Motor 30 drives reversible discharge pump 31 to supply liquid under pressure to the system. Pipe 31 connects the pump to cylinder 14 and pipe 32 connects the pump to chamber 22 in housing 19, whence the liquid passes through the pipe 33 to cylinder 10. Also, pipe 34 connects the other side of pump 30 to cylinder 11 while pipe 35 connects the same side to chamber 20 in housing 18, this chamber being connected to cylinder 13 by pipe 36. When the direction of fluid delivery is reversed from that shown in Fig. 1, it is obvious that pipe 35 will be a high pressure pipe instead of pipe 32 and it will be further noted that both of pipes 32 and 35 are connected to the chamber into which the respective valve 24 or 25 is moved when unseated and, therefore, the liquid under pressure will hold the valves upon their seats and the springs 28 need not be strong. Chambers 21 and 23 are connected together by by-pass pipe 37. A stop 38 is disposed to check movement of the crosshead at the end of each full stroke. As is shown in Fig. 8, the seats 39 for the valves 24 and 25 may be removed after detaching end closure 40 of the valve housing and a new seat installed whenever necessary due to wear. Since the liquid in chamber 21 is never under high pressure, packing around valve stem 26 to prevent leakage of fluid is not required, which reduces the cost of the valve assembly and also the labor of replacing such packings when worn.

It being assumed that pump 30 is operated to cause movement of fluid as indicated by the arrows adjacent the several pipes, the rams 12 and 15 will be actuated in the directions shown by the arrows thereon. At the end of the stroke, the lower (as seen in Fig. 1) end of crosshead 16 will push the stem 27 to unseat valve 25, which will permit the liquid under pressure to pass from chamber 22 to chamber 23, whence it will go through pipe 31, unseat valve 24, and return to pump 30 through chamber 20 and pipe 35, thus making the pressures in all the cylinders equal. If the crosshead should be continued in motion by the force of a wave against the rudder or for any other reason, it will be effectively checked upon contact with stop 38.

The mechanism shown in Fig. 2 is very similar to that in Fig. 1 except that the cylinder housings 18 and 19 are mounted on the cylinders 11 and 14 adjacent the pump. The various members in Fig. 2 are designated by primed reference characters corresponding to the analogous parts in Fig. 1. The operation is believed to be apparent without further description.

Fig. 3 discloses the present invention applied to a single pair of cylinders 41 and 42 with a cooperating ram 43. Fluid passes from pump 44 through pipe 45 to chamber 46 in valve housing 47 and thence by pipe 48 to cylinder 42. The return from cylinder 41 to pump 44 is through pipe 49, chamber 50, and valve housing 51 and pipe 52. It is to be understood that reversal of the discharge of the pump will cause a reversal in the flow of the liquid. The valve housings 47 and 51 have in them chambers 52 and 53 connected by passages in which are seated valves 54 and 55 with stems 56 and 57 attached thereto. These valves are held seated by springs 58 on the valve stems as above described. Crosshead 59 is connected to ram 43 and to a rotatable member, such as rudder post 44. The limit stops in this figure are designated by 60. The pipe 115 connects chambers 52 and 53 and, therefore, when one of the valves, say 54, is unseated the liquid under pressure in pipe 45 will pass through pipe 115 to chamber 53, unseat valve 55 and return to the pump through pipe 52. This action will, of course, be reversed when the discharge of the pump is reversed.

The form of invention illustrated in Fig. 4 is similar to that in Fig. 3 with the exception of the valve mechanism and, therefore, the parts common to the two are given the same reference characters. The valve housings 61 and 62 are connected to pump 44 by the pipes 45 and 52, but, in this instance the chambers 63 and 64 that are directly connected to the pump and are, therefore, under high pressure are so related to valves 65 and 66 that the pressure from the pump tends to open the valves and the springs 67 are not so strong as to prevent opening of the valves by the pressure. It follows, therefore, that when pipe 45 is the pressure pipe, valve 65 will be held open and oil under pressure will be present in chamber 70 but the effect of this pressure is to hold the valve 66 seated. When crosshead 59 approaches the end of the stroke it contacts stem 71 of valve 66, opens that valve, and permits the fluid under pressure in chamber 70 to move into chamber 64 and thence back to the pump through pipe 52, thus effectively by-passing the cylinders and bringing the ram 43 to rest. Under conditions of reverse flow of liquid, the valve 66 will be held open and the pressure will be transmitted through pipe 72 to chamber 73 which pressure will be connected to the suction side of the pump when crosshead 59 contacts stem 74 of valve 65.

An enlarged sectional detail view of the valve construction employed in Fig. 4 is disclosed in Fig. 9. The housing 61 has attached to it or formed integrally therewith an arm 75 that is turned over and provided with an aperture in line with the opening in the housing 61 through which valve stem 74 passes and thus the arm serves as one abutment for spring 67 and also as a guide for the valve stem 74. Inasmuch as the chamber 63 through one wall of which the valve stem passes is subjected to high pressure, a packing gland 75 is provided to insure against leakage around stem 74. The removable closure 40 and the replaceable valve seat 39 are the same as in Fig. 8.

In Fig. 5 the cylinders 76 and 77 coact with the ram 78 to which the crosshead 79 is connected by crosshead pin 80. The construction of the valve housings in this figure and their manner of connection to the system are the same as in Fig. 4 and the corresponding parts are, therefore, given the same reference characters. On the crosshead

pin 80 is secured a member 81 having perforated ears 82 into which are threaded bumper rods 83 and 84 each of which is held against accidental shifting by a nut 85. The bumper rods are aligned with valve stems 71 and 74 and serve to unseat the valves and by-pass the liquid from the pump at the end of a complete working stroke.

In some cases it is desirable to operate the by-pass valves by arms mounted on the crosshead adjacent the rudder stock but difficulty has been experienced heretofore in securing sufficient throw of the valve and the form of invention shown in Fig. 6 has, therefore, been devised to cure this defect. Pump 86 is connected by pipes 87 and 88 to the chambers 89 and 90 in the valve housing 91 wherein a shuttle valve 92 is mounted in a passage between the two chambers. At each end of the housing 91 is pivotally mounted a motion amplifying lever 93 having a long arm 94 provided with an adjustable element 95 to contact valve stem 96 and a shorter arm 97 lying at an angle to arm 94. The long arm 94 is provided with an adjustable element 98 disposed to be contacted by the adjustable bumper member 99 on arm 100 fixed to crosshead 101. When the parts are in the position shown, the output from pump 86 will flow through pipe 88 and pipe 102 to surround 103 while the return from cylinder 104 will pass through pipe 105 to pipe 87 and thence to the pump. However, when crosshead 101, driven by ram 106 reaches the end of its stroke the bumper member 99 will contact adjustable element 98 and swing the member 93 so that the member 95 will contact valve stem 89 and, since the arc through which the member 95 moves is much greater than the arc described by arm 97, the movement imparted to member 98 is amplified and the shuttle valve 92 is quickly moved to the left a sufficient distance to place the chambers 89 and 90 in free communication and, therefore, the output through pipe 88 merely circles through the valve housing 81 and back to the pump through pipe 87.

In Fig. 7 a somewhat similar arrangement is shown. The crosshead 101 has on it the arms 107 provided with a bumper element 108 which contacts one arm 109 of the pivoted double armed member 110 between the free end of the arm 109 and the pivot point thus making of the arm 109 a lever of the third class and imparting to the free end of the arm a movement much greater than that of the member 108. The adjustable bumper member 111 is mounted in arm 109 to contact stem 96 of the shuttle valve 92, the other parts of the shuttle valve mechanism being the same as in Fig. 6.

It is to be understood that the motion amplifying means for operating valves described in the preceding two paragraphs may be applied to opening valves of other types than the shuttle valves herein used for purpose of explaining the mode of operation of this mechanism.

It is to be noted that if the rudder is turned when the vessel is moving astern the pressure of the water on the rudder will tend to move it in the same direction and will thereby reduce the pressure in the cylinders acting to put the rudder over and concomitantly will increase the pressure in the other cylinders since the fluid in those other cylinders resist movement of the rudder by the water pressure. Under these conditions, when a by-pass valve is opened by the cross head the pressure in the working cylinder is insufficient to unseat the other by-pass valve which is 75

subjected to the greater pressure that is resisting movement of the rudder by the water pressure. Consequently, the by-passing of the liquid cannot take place until the stops 38 or 60 prevent movement of the rudder by the water pressure, which permits the pump to withdraw fluid from the cylinders subjected to suction and build up the pressure in the other cylinders sufficiently to unseat the by-pass valve not opened by the cross head, as is described in my Patent 1,969,736.

The invention described and claimed herein may be manufactured and used by or for the Government of the United States of America for governmental purposes without the payment of any royalties thereon or therefor.

I claim:

1. The combination with a mechanism that includes at least one pair of aligned cylinders, a ram operable in the two cylinders of a pair, means to supply fluid under pressure to one cylinder of a pair and simultaneously withdraw fluid from the other cylinder of the pair, a crosshead operatively connected to said ram, and a driven member connected to said crosshead; of a two-chambered valve housing mounted on each of two cylinders, said cylinders being operatively connected through said housings so that one cylinder receives fluid under pressure simultaneously with the withdrawal of fluid from the other of said two cylinders, there being a passage between the chambers in each housing; a valve seated in each of said passages and having a stem extending toward said cross head to be contactible thereby at the end of a stroke of said ram; means connecting to the cylinder upon which the other valve housing is mounted that chamber in each casing into which the valve moves when unseated; means connecting each of the last mentioned chambers to said fluid supply means; and means connecting together the other two of said chambers, whereby when a valve is unseated the pressures in said cylinders are equalized.

2. The combination with a mechanism that includes at least one pair of aligned cylinders, a ram operable in the two cylinders of a pair, means to supply fluid under pressure to one cylinder of a pair and simultaneously withdraw fluid from the other cylinder of the pair, a crosshead operatively connected to said ram, and a driven member connected to said crosshead; of a two-chambered valve housing associated with each of two cylinders, said cylinders being operatively connected through said housings so that one cylinder receives fluid under pressure simultaneously with the withdrawal of fluid from the other of said two cylinders, there being a passage between the chambers in each housing; a valve seated in each of said passages and having a stem extending toward said cross head to be contactible thereby at the end of a stroke of said ram; means connecting to the cylinder with which the other housing is associated that chamber in each housing into which the valve moves when unseated; means connecting each of the last mentioned chambers to said fluid supply means; and means connecting together the other two of said chambers, whereby when a valve is unseated the pressures in said cylinders are equalized.

3. The combination with a mechanism that includes a pair of aligned cylinders, a ram operable in both of said cylinders, means to supply fluid under pressure to one of said cylinders and

simultaneously withdraw fluid from the other cylinder, a crosshead operatively connected to said ram, and a driven member connected to said crosshead; of a two-chambered valve housing mounted on each of said cylinders, there being a passage between the chambers in each of said housings, a valve seated in each of said passages and having a stem extending beyond said housing to be contactible by said crosshead substantially at the end of movement of said ram, means connecting to the other cylinder that chamber in each housing into which the valve moves when it is unseated, means connecting the last mentioned chamber to the fluid supply means, and means connecting the other two of said chambers together.

4. The combination with a mechanism that includes two cylinders, means to supply fluid under pressure to either one of said cylinders and simultaneously to withdraw fluid from the other cylinder, means disposed in said cylinders to be actuated by pressure therein and operatively related to move simultaneously in relatively opposite directions in the respective cylinders, and a crosshead operatively connected to said last mentioned means; of fluid carrying means to connect said cylinders together, valve means connected between said fluid supply means and said cylinders and between said cylinders normally conditioned to prevent passage of fluid from the cylinder receiving fluid under pressure to the other cylinder, and slidable means contactible by said crosshead to condition said valve means at a predetermined phase in the operation of said mechanism to connect said cylinders together.

5. The combination with a mechanism that includes a pair of aligned cylinders, a ram operable in both of said cylinders, means to supply fluid under pressure to one of said cylinders and simultaneously withdraw fluid from the other cylinder, a crosshead operatively connected to said ram, and a driven member connected to said crosshead; of a valve housing associated with each of said cylinders, said housing having a first chamber and a second chamber with a passage between said chambers, a valve seated in each of said passages to be movable into the respective first chamber when unseated and having a stem extending through and beyond the second chamber, means connecting each of said first chambers to said fluid supply means, means connecting together said second chambers, the pressure in said second chambers being always relatively low whereby the fit of said stem in the wall of the chamber is sufficient to prevent leakage around said stem, said stems being contactible by said crosshead to unseat the valves.

6. The combination with a hydraulic power mechanism that includes a pair of aligned cylinders, a ram operable in both of said cylinders, a crosshead operatively connected at one end to said ram, and a rotatable member connected to the other end of said crosshead; of valve means to interconnect said cylinders including projecting valve unseating means, arms on said other end of the crosshead, means including a member pivoted at one end disposed to act upon said valve unseating means with its other end and contactible by an arm on said crosshead to actuate said member as a lever of the third class.

RALPH ERLING.
